UNITED STATES PATENT OFFICE.

HANS MIKOREY, OF SCHOENEBERG, GERMANY, ASSIGNOR TO THE FIRM OF W. GRAAFF & COMPANY, GESELLSCHAFT MIT BESCHRÄNKTER HAFTUNG, OF BERLIN, GERMANY.

CHEMICAL FIRE-EXTINGUISHER.

No. 799,796.

Specification of Letters Patent.

Patented Sept. 19, 1905.

Application filed January 21, 1905. Serial No. 242,162.

To all whom it may concern:

Be it known that I, HANS MIKOREY, a subject of the German Emperor, residing at No. 13 Wartburgstrasse, Schoeneberg, near Berlin, Germany, have invented a new and useful Improved Chemical Fire-Extinguisher, of which the following is a specification.

This invention relates to a chemical fire-extinguisher of that known type in which the fire-extinguishing substance is caused to act by the destruction of a vessel containing acid or the like, said destruction being effected by means of a striking device. This device, according to the invention, consists of a striking-weight and a spring in such a combination that the striking-weight when released freely drops upon the acid vessel and its striking power is increased by the action of the spring, which is kept tensioned by the striking-weight and set free by the release of the latter.

Referring to the accompanying drawings, Figure 1 is a side elevation and partial section of the apparatus in the operative position. Fig. 2 is a detail section of the releasing and vessel-striking device in the unreleased position. Fig. 3 is an end view of the ball-weight and head of the bolt seen from below. Fig. 4 is view similar to Fig. 2 with the striking device in the released position; and Fig. 5 is an end view similar to Fig. 3, showing the ball-weight and the head of the bolt in the respective released position.

The apparatus consists of a casing or receptacle A filled with the liquid, which when the apparatus is operated is ejected through a suitable nozzle B. The releasing and vessel-striking device is secured in the side wall of the apparatus by means of a lid or cover b, over which the yoke-shaped handle c of the apparatus is arranged. The cage or holder a is supported beneath the lid b within the apparatus and contains the acid vessel l. In the middle of the lid a turnable bolt d extends through a stuffing-box h into the holder a and is vertically directed to the tapering end k of the acid vessel l. The said bolt in order to be turned is provided at its outer end with a hand-lever g, while it terminates within a prismatic head f, which serves as a stop for the ball-weight e slidable thereon. The guiding-passage of the weight through which the bolt d

extends and the prismatic head f have the same cross-section, so that the head only supports the weight when located transversely to 55 the guiding-passage, Figs. 2 and 3, but releases the weight when located longitudinally, Figs. 4 and 5, so that the weight can slide down off the bolt beyond the head. In order to obviate a turning of the weight on the bolt, 60 whereby the weight is liable to slide down unintentionally and also to reliably guide the weight in the desired direction when sliding downward, guide-rods may be provided, as shown, which are parallel to the bolt d and 65 attached to the lid b. A spring i is coiled round the bolt d, said coils being firmly compressed between the weight and the lid b, so that the spring is then tensioned.

The hand-lever g serves for the release of 70 the striking device when the apparatus is to be operated. For this purpose the bolt d is turned, by means of the hand-lever g, at an angle of ninety degrees—i. e., from the position as shown in Fig. 3 into the position according to Fig. 5. As in this position the head of the bolt and the guiding-passage of 75 the weight coincide, the latter is thus released and drops down freely, the starting impulse being given by the spring. By means 80 of the guide-rods the path of the dropping weight is against the tapered apex k of the acid vessel. Owing to the impulse which is transmitted by the spring i to the weight after the release the striking power is increased, 85 and in consequence of the accelerating momentum of the weight, assisted by the action of the spring, the total destruction of the acid vessel l is insured. Fig. 4 shows the parts after the release has taken place. The shape 90 of the weight is not essential for carrying out the invention; but the spherical form is preferred.

Having now particularly described and ascertained the nature of my said invention and in what manner the same is to be performed, I declare that what I claim, and wish to secure by Letters Patent, is—

A chemical fire-extinguisher, the combination of a casing forming the liquid-receiver, 100 an acid vessel located in a holder within the said casing, a weight slidably arranged above the acid vessel within the casing and provided with longitudinal passages, guide-rods se-

cured to the top of the holder and passing through several of the passages to guide the weight a turnable bolt extending through a stuffing-box of the casing and through one of 5 the said passages and terminating with a head which forms a releasable stop underneath the weight, so as to normally hold the latter in a suspended position, while by the turning of the bolt, the weight can be released so as to 10 strike the acid vessel and destroy it for oper-

ating the fire-extinguisher, substantially as described and shown in the drawings.

In testimony whereof I have signed my name to this specification in the presence of two subscribing witnesses.

HANS MIKOREY.
